UNITED STATES PATENT OFFICE.

GEORGE A. ROBERTSON, OF YOUNGSTOWN, OHIO.

SAND-REMOVING DEVICE.

Application filed March 28, 1925. Serial No. 19,070.

To all whom it may concern:

Be it known that I, GEORGE A. ROBERTSON, a citizen of the United States, residing at Youngstown, in the county of Mahoning 5 and State of Ohio, have invented new and useful Improvements in Sand-Removing Devices, of which the following is a specification.

This invention relates to improvements 10 in sand removing devices and contemplates the provision of a device which may be readily and easily inserted within a well tubing and upon rotations therein will remove the sand and rust from the bottom of 15 the well and collect the same therein in order that the entire tool may then be withdrawn with the sand, rust, or other extraneous matter.

Another object of the invention is the 20 provision of filed cutting blades arranged upon the outer sides of the tool and which when rotated within the well tubing will engage the side walls of the well tubing and convey the sand and rust upwardly along 25 the outer and upper sides thereof and into such passages into the body of the tool.

A further object of the invention resides 30 in the provision of oppositely extending helically pitched cutter blades arranged upon the bottom of the device and which will not only cut and remove the sand and rust from the bottom of the well but convey the same into the device through trap doors arranged therein and which will automatically close when the tool is given a slight upward pull so that the entire tool may be removed from the well without danger of the extraneous matter from again entering 35 the well.

With the above and other objects in view, the invention further includes the following novel features and details of construction, to be hereinafter more fully described, 40 illustrated in the accompanying drawing and pointed out in the appended claims.

In the drawing:

Figure 1 is a side elevation of the invention shown inserted within a well tubing.

Figure 2 is a transverse section taken on line 2—2 of Figure 4.

Figure 3 is a transverse section taken through the invention as shown in Figure 1 of the drawing.

Figure 4 is a similar view taken on line 4—4 of Figure 1.

Figure 5 is a bottom plan view of the invention.

Figure 6 is an enlarged vertical sectional view.

Referring to the drawing in detail, wherein like characters of reference denote corresponding parts, the reference character 10 indicates a portion of a well tubing which is of the usual and well known construction and is used primarily for preventing the dirt or other extraneous matter upon the sides of the well opening, to fall within the well and so unnecessarily pollute the water within the well.

In order to provide such means as may be inserted within this well tubing 10 in order to remove the rust from the sides thereof and sand or other extraneous matter from the bottom of the well, I provide a 75 tubing 11 having a bottom 12 and a removable closure cap 13 upon the upper end thereof; this closure cap 13 further includes a lifting or turning bar 14 extending upwardly and centrally thereof and provided with a cork handle 15 upon the upper end thereof and a loop or ring 16 which may be readily and easily applied to a block and tackle which may in turn be connected with a tripod or derrick upon the surface above 80 the well in order that the tool may be raised and lowered within the well for removing the matter therefrom or to so restrict the entrance of the tool within the well as may be desired. Arranged upon the outer sides 85 of the tubing 11 and spiraled thereon are cutter blades 17 which extend from the removable closure 13 of the tubing 11 and extend below the end of the same and terminate in oppositely disposed cutting end 90 portions 18 and 19 respectively. These end portions 18 and 19 are adapted to dig into the bottom of the well and when rotated therein will tend to convey the extraneous matter or the like upwardly upon the upper sides of its blades and in so doing will permit the mud, sand, or other extraneous matter to pass between auxiliary cutter blades 20 which are struck outwardly from the sides of the tubing 11 and fall within 95 the latter for collection.

There is also provided upon the lower end or bottom of the tubing 11 a plurality of blades which are none other than the blades 18 and 19, and as clearly illustrated 100 in Figure 2 of the drawing, the cutter blade 18 is shown struck from the bottom of the

tubing 11 and including an auxiliary closure valve, flap valve, as indicated at 21 which is hinged or otherwise secured to the inner face of the bottom 12 and which will close when the rotation of the tool is stopped and prevent the mud, sand and the like from falling out of the tubing 11.

In the use and operation of the present invention, it will be clearly apparent that 10 upon inserting the tubing 11 into a well casing 10 or the like, and upon the successive rotations of the tubing 11 through the instrumentality of the bar 14 and 15, that the spiral cutting blades 17 will engage 15 the side walls of the well pipe 10 in order to remove the rust therefrom and the end portions of the same, namely, the blades 18 and 19 respectively will engage the bottom portions of the well and convey the 20 mud, sand and other extraneous matter collected in the bottom of the well, upwardly upon the blades 17 and between the auxiliary cutting blades 20 and into the tubing 11 for collection.

25 It is also manifest that the blades or end portions 18 and 19 respectively when rotated in opposite directions within the well, all of the mud, sand and other matter will pass between the same and enter the tubing 11 and past the flap valves 21 whereby the mud, sand and the like will collect in the tubing 11 and may be withdrawn with the device from the well and emptied after removing the closure cap 13.

30 35 The invention is susceptible of various changes in its form, proportions and minor details of construction, and the right is herein reserved to make such changes as properly fall within the scope of the appended claims.

Having thus described my invention what is claimed is:

1. A sand removing device of the character described comprising a tubular casting including a bottom and removable 45 closure cap, a plurality of spiraled cutting blades arranged upon the outer side walls of the tubing, a plurality of auxiliary cutting blades struck outwardly from the outer side walls of the tubing and adjacent the 50 spiraled cutting blade, and a pair of oppositely disposed cutter blades arranged upon the bottom of the tubing and including flap valves arranged therewith substantially as set forth.

2. A sand removing device for wells and the like comprising a hollow tubing including a bottom and removable closure cap therefor, an operating bar extending upwardly and centrally from the closure cap, 60 a cross bar secured to the upper end of the operating bar, a plurality of oppositely disposed cutter blades spiraled around and extending the entire length of the tubing, a plurality of auxiliary cutter blades struck 65 outwardly from the outer sides of the tubing and arranged in direct proximity to the spiraled cutter blades for removing such extraneous matter as may be collected from the spiraled cutter blades, and a pair of 70 oppositely disposed cutter blades arranged upon the bottom of the tubing and adapted to remove the sand from the bottom of a well and allow the same to pass within the tubing and held against accidental displacement therefrom.

In testimony whereof I affix my signature.

GEORGE A. ROBERTSON.
